(57) **CLAIM**

The ornamental design for a voltage detector, as shown and described.

DESCRIPTION

FIG. 1 is a perspective view of the voltage detector;
FIG. 2 is a left side elevational of the voltage detector;
FIG. 3 is a right side elevational of the voltage detector;
FIG. 4 is a top plan view of the voltage detector;
FIG. 5 is a bottom plan view of the voltage detector;
FIG. 6 is a front elevational view of the voltage detector; and,
FIG. 7 is a rear elevational view of the voltage detector.
